METAL RECOVERING MACHINE

Eric J. Ohman, Anchorage, Territory of Alaska

Application May 14, 1946, Serial No. 669,644

1 Claim. (Cl. 209—465)

1

The present invention relates to improvements in machines for recovering metals from ores and more particularly for the recovery of precious metals such as gold.

An object of the invention is to provide a metal recovery machine of generally improved construction.

Another object of the invention is the provision of a metal recovery machine which is highly effective in separating metal from the gangue of the ore.

A further object of the invention is to provide a machine of the aforesaid character which is relatively rapid and efficient in operation.

Other objects and advantages of the invention will become apparent as the description progresses.

In the accompanying drawings forming a part of this specification and in which like numerals are employed to designate corresponding parts throughout:

Figure 1 is a side elevational view of the machine having parts thereof broken away to illustrate the interior construction.

Figure 2 is a fragmentary longitudinal section taken on line 2—2 of Figure 3.

Figure 3 is a front end elevational view of the machine.

Figure 4 is a fragmentary rear elevational view as viewed from line 4—4 of Figure 2.

Figure 5 is a vertical sectional view taken on line 5—5 of Figure 1.

Figure 6 is a fragmentary sectional view taken on line 6—6 of Figure 4.

Figure 7 is an end elevational view of the machine casing.

Figure 8 is a bottom plan view of the same.

Figure 9 is a horizontal sectional view taken on line 9—9 of Figure 2 showing pulverizing means added thereto.

Figure 10 is a side elevational view of a feed chute.

Figure 11 is a bottom plan view of a sluice member.

Figure 12 is a bottom plan view of the main hopper.

Figure 13 is a side elevational view of an auxiliary detachable reducer fitting.

Figure 14 is a side elevational view of an auxiliary hopper, and

Figure 15 is a fragmentary top plan view of a conveying chute.

Referring to the drawings, wherein for the purpose of illustration is shown a preferred example of the invention, 20 designates each of four frame

2

uprights supported on horizontal bottom skids 21, constituting the main framework of the machine. At an elevated position on the frame uprights is secured a casing composed of top and bottom sections 22 and 23, respectively, detachably assembled by flange connections 23' and having a funnel shaped bottom 24 embodying sloping walls merging into a central flange 25 of annular form. The end walls of the top and bottom sections 22 and 23, respectively, are provided with circular openings 26.

Extending horizontally through the casing sections 22 and 23 with the ends projecting outwardly of the openings 26 thereof is a cylindrical perforated barrel 27 forming an upper receiving hopper provided, adjacent each end, with an internal flange 28 bearing against the end walls of the casing sections and, at corresponding positions, with relatively narrow inwardly directed end flanges 29. On an intermediate portion of the barrel 27 is mounted an annular V-shaped deflecting ring 30 over the intermediate portion of which is securely mounted an exteriorly toothed annular gear 31. This barrel is rotatably supported on the frame by means of rollers 32, mounted on rectangular shaped vertical brackets 33 fastened to the frame, and engaging the projecting end portions of the barrel.

Trained over the gear 31 and engaging the teeth thereof is an endless drive chain 34 extended laterally to engage a sprocket wheel 35 secured on an elevated rotary shaft 36 journaled horizontally in bearing brackets 37. This chain is also trained over a lower sprocket wheel 38 fastened on a transversely extending shaft 39 journaled in bearing brackets 40 fastened to the frame uprights 20.

At one end of the cylindrical member 27 is mounted a horizontally disposed endless conveyor 41 operable over a roller 42 and having mounted on the frame thereof a transversely extending rod 43. To this conveyor frame is attached one end of a feed chute 44 provided, at its inner end, with bearing apertures 45 and arcuate slots 46 in the opposed side walls thereof. The shaft 47 of the conveyor roller 42 is journaled in the frame and driven by gear connection with the drive shaft 36 and extends through the apertures 45 for pivotally supporting the chute 44 while the end projections of the rod 43 engage the slots 46 and threaded receive nuts 48 on the end portions for securing the chute at desired inclination for feeding material into the barrel.

To a cross bar 49 at each side of the frame 55 is connected, by pivot shafts 50, the inner ends

of a pair of sluice frames 51 which are designed to assume a downwardly inclined outwardly directed position. Each of these two frames 51 is provided, at its inner portion, with a carrier bottom 52 and side boards 53 arranged vertically at each side thereof. The outer end of one frame 51 is pivotally connected, by pivot bolts 54, with the outer slotted ends of an extension sluice 55, at the front of the frame. This latter sluice is designed to direct material onto a transversely extending endless conveyor 56 adjustably supported in vertically inclined position by connection with the frame of the slotted extension 57 of the opposite side sluice 51. The inner roller 58 of the conveyor 56 is secured on a transverse shaft 59 rotatably journaled in bearing brackets 60 on the frame, this shaft having a bevel gear 61 fixed on one end disposed to mesh with a complementary bevel gear 62 secured on the lower end of a vertical shaft 63 journaled in brackets 64 on the frame. At the upper end of the shaft 63 is secured a bevel gear 65 in mesh with a complementary bevel gear 66 secured on one end of the transverse shaft 39. This latter shaft has fixed, on the intermediate portion thereof, a toothed sprocket wheel 67 over which is trained an endless drive chain 68 connecting the shaft 39 with the shaft 69 of an electric drive motor 70, mounted on a lateral extension 71 of the frame.

On the opposite end of the shaft 39 is secured a bevel gear 72 in mesh with a complementary bevel gear 73 on one end of a horizontal stub shaft 74 journaled in a bearing sleeve 75. This stub shaft drives, through the medium of bevel gears 76, a rotary socket journaled in a bearing sleeve 77 mounted at the end of the barrel on a bracket 78 and in longitudinally opposed relation to a bearing sleeve 79 on a bracket 80 fastened to the opposed end of the frame. This drive connection is designed to releasably engage a shaft 81 carrying, at longitudinally spaced intervals thereon, a plurality of concavo-convex disks 82 which may be removably disposed to extend through the lower portion of the barrel.

Within the upper portion of the barrel 27 is extended a horizontally mounted pipe 83 making connection at one end with a source of fluid supply, this pipe having longitudinally spaced apertures 84 designed to form sprinkler jets.

To the funnel shaped casing bottom 24 is connected a cylindrical depending apron 85 fastened by vertically extending brackets 86 providing a lower hopper. To the lower portion of this apron is detachably connected a reducer fitting 87 having a cylindrical top flange 88 fastened circumferentially about the lower portion of the apron 85 by bayonet slot connections having a funnel shaped bottom wall tapering to a bottom outlet boss 89 of substantially reduced diameter. In the fitting 87 is supported a circular hopper 90 comprising an upper flaring section 91 merging into a lower abruptly tapered section 92 which terminates in a flanged outlet 93 which is exteriorly screw threaded. This hopper is supported concentrically of the apron 85 on the reducer fitting and spaced therefrom through the medium of a plurality of angular approximately V-shaped support brackets 94, shown to advantage at Figure 2. A flanged pan 95 is adapted for threaded connection with the outlet 93. When treating ores of a particular character this assembly is modified by fastening, with bayonet slot and pin connections to the flange 89 of the reducer an auxiliary reducer fitting 96

similar to the fitting 87 but of a reduced size. Below this fitting is supported, by depending bars 97, an auxiliary hopper 98 having an exteriorly threaded outlet 99 normally covered by a flanged pan 100.

To the pins on the flange 89 may be connected the inner annular head portion 101 of an inclined and tapered chute 102, the purpose of which will be hereinafter described.

10 To the funnel shaped bottom structure 24 of the casing is fastened a horizontally arranged spider frame 103 having a central aperture in which is journaled a tubular vertically disposed shaft 104 having fastened on its upper end a bevel gear 105 in mesh with a bevel pinion 106 fixed on the inner end of a transversely disposed rotary shaft 107, driven through the medium of intermeshing bevel gears 108 and 109. The gear 109 is fixed on the lower end of a stub shaft 110 having driving connection with the transverse shaft 39 through intermeshing bevel gears 111 and 112. On the lower portion of the tubular shaft 104 is fastened a horizontally disposed plate 113 apertured for connection thereto

15 20 25 30 35 40 45 50 55 60 65 70 75

of a plurality of stirring elements 114, 115 and 116. These elements may be composed of rods having inner portions depending from the plate 113 and formed so that the element 115 extends straight downward to revolve within the center outlet of the hopper 90 while the element 114 is bent to provide an upturned finger disposed to revolve exteriorly of and immediately adjacent the funnel outlet 25. The third stirring element 116 is bent to form an angular upwardly inclined stirring finger arranged to revolve adjacent the walls of the hopper 90.

When the auxiliary attachments are mounted on the machine an extension shaft 117 is secured in vertical arrangement with its upper portion fitted in and secured to the shaft 104 and carries on its lower portion a horizontal plate 118 having attached thereto a plurality of stirring elements 119 shaped in accordance with the elements 114, 115 and 116 but of reduced size, for rotation in the auxiliary hopper 98 and its outlet 99.

The machine operates as follows:

For treating sand or gravel metal containing ore the apparatus is employed in the arrangement shown at Figures 1 and 2, the ore being delivered to the machine on the elevated conveyor 41 from whence it is discharged onto the chute 44 which conducts it onto the center portion of the revolving barrel 27. At this point the material is wetted by water or other liquid sprinkled from the pipe 83, the large solid particles of ore, such as boulders and the like, are worked to the ends of the barrel and carried, through the medium of the sluices 51; onto the waste conveyor 56 which carries the same to a dumping station.

The finer particles of the ore, pulverized by the rotation of the barrel, drop through the perforations therein and flow through the funnel shaped bottom 24 and the outlet 25 thereof into the hopper 90 where the wetted ore is subjected to agitation and stirring by the revolving finger elements. The lighter gangue of the ore, that is, the material of relatively low specific gravity, is floated over the top of the hopper and washed downwardly between the same and the skirt and funnel members 85 and 87, constituting the tailings of the ore which are carried away by the chute 102. The heavier metallic particles separated and concentrated in the hopper settle into the

bottom outlet portion and in the pan 95 attached to the hopper and are recovered by periodically removing and emptying this pan.

When treating clay ore, the disk carrying shaft 81 and the auxiliary funnel and hopper structures are attached to the machine so that the rotating disks 82 facilitate the pulverization of the ore in the rotary barrel while the agitation and stirring of the slime is repeated, after passage through the hopper 90, in the auxiliary hopper 98 to facilitate separation of the metallic particles from the more tenaciously clinging clay gangue.

Thus, my improved machine thoroughly agitates the ore to effectively concentrate and recover metals, and more especially precious metals, from the gangue and is designed to effect such concentration and recovery rapidly and with the utmost efficiency.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

In a fine gold recovering machine concentrator, the combination which comprises an upper receiving hopper having a cylindrical wall with a conical shaped section at the lower end and with a cylindrical band depending from the lower part of the said conical shaped section, a lower hopper having a cylindrical wall carried by and extended downwardly from the said depending band of the upper hopper, an auxiliary hopper having a conical shaped wall with a horizontally disposed lower end and having a cylindrical neck depending from the center of the said lower end, a pan providing a closure removably secured to the lower end of the neck of the auxiliary hopper, a funnel shaped feed chute having a depending cylindrical wall positioned in the upper end of the

upper hopper, a vertically disposed centrally positioned shaft extended upwardly through the said upper and lower hopper and feed chute and into the said auxiliary hopper, an agitating finger carried by the shaft, extended outwardly and upwardly and spaced from the inner surface of the wall of the said upper hopper, a U-shaped finger carried by the shaft and extended around the depending cylindrical wall of the feed chute, an agitating finger also carried by the shaft and positioned to travel around the inner surface of the cylindrical band of the upper hopper, and corresponding agitating elements also carried by the shaft and positioned to coact with the inner wall surface of the auxiliary hopper and outer and inner surfaces of the cylindrical wall of the lower hopper.
